UNITED STATES PATENT OFFICE.

HUDSON J. METZ, OF HABANA, CUBA.

CARRIAGE-SHIFTING MECHANISM FOR TYPE-WRITING MACHINES.

1,201,213.

Specification of Letters Patent. Patented Oct. 10, 1916.

Application filed February 11, 1916. Serial No. 77,772.

To all whom it may concern:

Be it known that I, HUDSON J. METZ, a citizen of the United States, residing at Habana, Cuba, have invented certain new and useful Improvements in Carriage-Shifting Mechanism for Type-Writing Machines, of which the following is a specification.

This invention relates to the subject of typewriting machines, and more particularly to an attachment for typewriting machines by means of which the carriage thereof may be readily shifted and spaced through the medium of foot operated mechanism.

The invention contemplates in its general organization a treadle mechanism that may be readily disposed beneath the stand of a typewriting machine in position to be readily actuated by the foot of the operator of the typewriting machine, the invention being of such a nature that the same can be readily shifted and adjusted to suit the convenience of the operator, and being provided with means whereby the same may be connected to the stand and to the floor, the connection with the stand being of a flexible nature to permit the treadle mechanism to be bodily shifted to angular positions relative to the stand.

One simple and practical embodiment of the invention is shown in the accompanying drawings, wherein—

Figure 1 is a view in front elevation of the improved carriage shifting mechanism shown (attached) to a typewriting machine, the typewriting machine and its stand being indicated by dotted lines. Fig. 2 is a detail elevation of the treadle mechanism. Fig. 3 is a sectional view taken substantially on a line 3—3 Fig. 2. Fig. 4 is an enlarged transverse sectional view showing the manner of adjustably connecting the two members of the supporting standard. Fig. 5 is a sectional view taken substantially on line 5—5, Fig. 2. Fig. 6 is a detail fragmentary sectional view taken substantially on the line 6—6, Fig. 2. Fig. 7 is a detail perspective view showing the manner of flexibly connecting the supporting standard to the stand of the typewriting machine.

The improved carriage shifting mechanism, in its preferred embodiment, comprises a base support 1 which may be equipped with openings 2 for the reception of floor engaging spurs or the like to normally pre-

vent slipping of said base support. Adjacent one end portion the support 1 has an upstanding supporting post 3 riveted or otherwise rigidly attached thereto, said post 3 having a treadle lever 4 pivoted to its upper end, the rear end of said lever being provided with a treadle 5. The base support 1 at its forward end terminates in a bracket arm 6 that is disposed in a plane higher than said support 1, and has a pulley 7 pivoted thereto.

Adjacent the bracket arm 6 the base support 1 may be provided with slots 8 adapted for selective engagement by the end hook 9 at the lower end of the lower section 10 of a supporting standard designated in its entirety by the numeral 11. The standard 11 is preferably composed of two sections the upper one being designated by the numeral 12, and the lower one by the numeral 10 as aforesaid. The standard 11 is preferably formed of sheet metal that is shaped to permit the sections 10 and 12 to have sliding interlocking engagement as indicated in Fig. 4 of the accompanying drawings, a set screw designated by the numeral 13, being employed to lock the section in the desired adjusted position. Section 12 at one edge portion is provided with a laterally projected ear 14, and its upper end is preferably rolled as indicated at 15 for pivotal engagement with the pintle 16, carried by the rounded rear end of a flat strap 17, the strap being formed of a single piece of material that is folded on itself and provided with openings 18 for the reception of suitable fastenings for attaching the said strap to the undersurface of the top of a stand 19.

It will be observed from the foregoing description that the described manner of attaching the standard 11 to the stand 19 is in effect a pivotal connection between the standard and stand which permits the treadle mechanism including the standard to be shifted relatively to said stand.

A spring 20 connects the forward end of treadle 4 with the ear 14 of standard 11 to maintain a tension on a carriage shifting cable 25, to be referred to.

The typewriting machine has been designated generally by the numeral 21 and one end of the upper portion of its frame is equipped with a laterally projecting bracket 22 terminating in an upstanding post 23 to which a pulley 24 is pivotally connected.

The cable 25 passes over pulleys 7 and 24, the lower end of the cable being connected to the forward end of lever 4 and the upper end of said cable being connected to a line 5 spacing hook or the like 26 forming a part of the carriage 27 of the typewriting machine.

As shown in Fig. 1 of the drawings, the carriage 27 is at the limit of its movement 10 to the left of the frame of the machine and the forward end of the treadle lever 4 is depressed. To shift the carriage to the opposite portion of the frame, the treadle 5 is depressed by the operator, causing the 15 forward end of lever 4 to rise and thereby exert a pull on cable 25 that shifts the carriage from the left to the right position relative to the frame of the typewriting machine, and at the same time, by operating 20 hook 26, effect the necessary or desired line spacing.

It is preferred that the base 1, post 3, treadle and treadle lever 4, standard 11, and bracket 22 be formed from sheet metal, as 25 the same can be readily stamped or punched to the desired shape, and quickly assembled in operative position, although it is to be understood that the invention is not necessarily restricted to the use of sheet metal.

30 From the foregoing description it will be apparent that this invention is one that can be used in connection with any form of typewriting machine, and that through the use of the adjustable standard 11, the same 35 may be adjusted vertically in accordance with the heights of the top of the stand used, and that through the use of the described hinge connection 17, the treadle mechanism may be shifted laterally relatively to the stand.

I claim as my invention—

1. A carriage shifting and spacing mechanism for typewriting machines comprising a floor engaging support provided with cable-guiding means, a treadle carried by the support, an adjustable standard carried by the support and provided with means for pivotally engaging a typewriting machine stand, a carriage shifting and spacing cable 45 operated by the treadle and engaging the 50

cable guiding means, and a spring connection between the treadle and the standard.

2. A carriage shifting mechanism for typewriting machines comprising a support having an outwardly projecting elevated 55 bracket arm at one end, a pulley carried by the arm, a treadle carried by the support, a standard carried by the support, means for pivotally connecting the standard to a typewriting machine stand, a bracket 60 carried by the frame of a typewriting machine, a pulley carried by the bracket, and a cable engaging the pulley and having its ends attached to the spacing mechanism of the carriage of a typewriting machine and 65 to the treadle for shifting and spacing the carriage, respectively.

3. A carriage shifting and spacing mechanism for typewriting machines comprising a flat base having one end shaped 70 to form an outwardly projecting elevated bracket, a cable guide carried by the bracket, a treadle pivotally connected to the base, a carriage shifting cable attached to the treadle and engaging the guide, a stand- 75 engaging standard carried by the base, and a spring connection between the treadle and standard.

4. A carriage shifting mechanism for typewriting machines comprising a support 80 having an elevated bracket arm at one end, a pulley carried by the arm, a treadle carried by the support, a standard carried by the support, means for pivotally connecting the standard to a typewriting machine 85 stand, a bracket carried by the frame of a typewriting machine, a pulley carried by the bracket, and a cable engaging the pulley and having its ends attached to the spacing mechanism of the carriage of a type- 90 writing machine and to the treadle for shifting and spacing the carriage respectively.

In testimony whereof I have affixed my signature in presence of two witnesses.

HUDSON J. METZ.
